UNITED STATES PATENT OFFICE.

LOUIS S. RIZER, OF SPRINGFIELD, OHIO.

MOTOR.

1,140,532.

Specification of Letters Patent. Patented May 25, 1915.

Application filed March 2, 1914. Serial No. 821,973.

To all whom it may concern:

Be it known that I, LOUIS S. RIZER, a citizen of the United States, residing at Springfield, in the county of Clark and State of Ohio, have invented certain new and useful Improvements in Motors, of which the following is a specification, reference being had therein to the accompanying drawing.

This invention relates to motors and more particularly to water motors of that type designed for the operation of washing machines, water lifts and the like.

The object of the invention is to provide a motor of this kind in which the valves may be shifted without the use of springs; in which the action of the motor will be positive; and in which the mechanism will be of such a character that it will require no delicate adjustments and will not be likely to become disarranged and to be rendered inoperative in service.

To this end it is a further object of the invention to provide means for actuating the valve, which controls the flow of fluid to and from the motor, by fluid pressure and to control this pressure by the movement of the piston of the motor so that the flow of fluid will be reversed at the end of each stroke of the motor piston.

In the accompanying drawings, Figure 1 is a side elevation of a motor embodying my invention; Fig. 2 is a top, plan view of the same; Fig. 3 is a transverse section, taken on the line 3 3 of Fig. 1; Fig. 4 is a longitudinal section taken on the line 4 4 of Fig. 2; Fig. 5 is a section taken on the line 5 5 of Fig. 2 and looking in the direction of the arrows; Fig. 6 is a section taken on the line 6 6 of Fig. 2; and Fig. 7 is a section taken on the line 7 7 of Fig. 2 and looking in the direction of the arrows.

In these drawings I have illustrated one embodiment of my invention and have shown the same as applied to a reciprocating motor which is arranged in a vertical position but it will be understood that this type of motor is chosen for the purposes of illustration only and that neither the type of motor nor the manner of its arrangement is essential to the invention but may be varied at will.

In the present embodiment of the invention I have shown the motor as comprising a cylinder consisting of the usual cylindrical body portion 1 and cylinder heads 2 and 3 which may be connected with the cylindrical

body portion in any suitable manner. Each cylinder head has an opening provided with a stuffing box 4 through which passes a piston rod 5. One end of the piston rod is adapted to be connected with the device which is to be operated and the other end of the piston rod controls the valve-shifting devices. It will be obvious, however, that the rod could be projected through one end of the cylinder only and that the valve shifting device could be controlled by the same portion of the rod which is connected with the work.

The motor, as shown, is mounted upon a bracket 6 which, in turn, may be mounted upon a suitable support, such as the hinged top for a washing machine. Arranged adjacent to and preferably alongside of the cylinder 1 is a valve casing 7 having formed therein two valve chambers 8 and 9. The valve chamber 9 communicates with the cylinder 1 on opposite sides of a piston 10 mounted within the cylinder 1 and connected with the rod 5. The communication between the valve chamber 9 and the cylinder is through a two part chamber or conduit 11 which, in the present form of the device, is arranged between the valve chamber 9 and the cylinder. This two part chamber is provided at its opposite ends with ports 12 and 13 connecting the same with the interior of the cylinder 1 at the opposite ends thereof. The two parts of the chamber or conduit 11 are respectively provided at their adjacent ends with inlet and exhaust passages 14 and 15 and 16 and 17 connecting said two parts of said chamber with the valve chamber 9. Mounted in the valve chamber 9 is a piston valve 18 having three annular ports, one near the center and one near each end thereof. The central port 19 is an inlet port and is adapted to be moved into registration with either of the inlet ports 14 and 16 leading to the chamber 11 and is always in communication with a passageway 20 leading to the valve chamber 8 which, in turn, is connected with a source of supply by means of an inlet passageway 21. The other annular ports, 22 and 23, are exhaust ports and are so arranged that when the inlet port 19 is in register with the port 16 of the chamber 11 the exhaust port 22 will register with the port 15 of the chamber 11, and when the port 19 is registered with the port 14 the exhaust port 23 will register with the port 17 of the chamber 11. The valve chamber 9

is also connected with an exhaust chamber 24 by means of ports 25 and 26 arranged to communicate with the exhaust ports 22 and 23 of the valve 18 when these ports are 5 in register, respectively, with the ports 15 and 17 of the chamber 11, thus permitting the fluid to exhaust from the cylinder 1 through one part of the chamber 11 and the exhaust port of the valve to the exhaust 10 chamber 24 which is connected with the exhaust pipe by means of a nipple 27. While the fluid is thus exhausting from the cylinder on one side of the piston it is passing 15 to the cylinder on the other side of the piston through the passageway 20, inlet port 19 of the valve 18 and the other part of the chamber 11.

The piston valve 18 is moved from one 20 position to the other by means of the pressure of the motor fluid and to this end the valve chambers 8 and 9 are connected one to the other, on opposite sides of the passageway 20, by passages 28 and 29, these 25 passageways communicating with the valve chamber 9 beyond the limits of movement of the piston valve 18. The movement of this valve is, in the present instance, limited by means of hollow extensions 30 formed on the heads closing the ends of the valve 30 chamber and spaced away from the walls of the valve chamber. These hollow extensions are provided with ports 31 to connect the interior thereof with the valve chamber proper and thus expose substantially the 35 full end of the valve to the pressure of the water that enters through the ports 28 and 29. The valve chamber 8 communicates with the source of fluid supply, which communication, in the present instance, is by 40 means of the inlet passage 21 which enables the chamber to be connected with a supply pipe. Mounted within the valve chamber is a suitable valve to control the flow of fluid through the valve chamber 9. This valve is 45 here shown in the form of a piston valve 33 and is provided with a wide central annular port 34 by means of which the supply pipe or inlet 21 is always connected with the 50 passageway 20 so that the water always has free passage from the supply pipe through the valve chamber 8 and passage 20 to the valve chamber 9. The valve 33 has a longitudinal passageway 35 which extends 55 through one end of the valve and communicates with the interior of the valve chamber at the other end of the valve by means of ports 36. The passageway 35 is connected with the source of fluid supply by means of a port 37 and, consequently, there is a 60 constant fluid pressure at both ends of the longitudinal passageway 35 and through whichever of the ports 28 or 29 is open. With the valve 33 in the position shown 65 in the drawings the passageway 35 is in communication with the port 28 at the upper

end of the valve chamber 8 and the fluid has passed through the port 28 into the valve chamber 9 above the piston valve 18 and has moved this valve downward into the position shown, so that the fluid is entering the cylinder 1 beneath the piston 10. As the piston rises in its cylinder it will 70 shift the valve member 33 to reverse the flow of water from the valve chamber 8 to the valve chamber 9. To this end the piston rod 5, which projects above the cylinder 1, has a slotted arm 38 which extends about a valve stem 39 connected with the valve member 33 and having stops 40 between which the arm 38 moves. These stops are so 75 arranged that when the piston 10 approaches the limit of its movement in either direction it will engage one or the other of the stops and shift the valve 33. The upward movement of the piston will cause the 80 valve 33 to be moved upward, thus cutting off the port 28 from the passageway 35 of the valve and connecting the port 29 with that passageway. It will be noted that the arrangement of the valve 33 is such that those parts thereof lying between the ports 44 and 45 and the respective ends of the conduit 35 will, at one position of the valve, 85 completely close both the ports 28 and 29, leading to the valve chamber 9, thereby 90 causing the one port to be completely closed before the other is opened. As a result the water will enter the valve chamber 9 beneath the piston valve 18. The valve will be shifted to bring the inlet port 19 into registration with the port 14 of the upper part of the chamber 11, which communicates with the cylinder 1 above the piston. To permit 95 this movement of the piston valve 18 it is necessary that the water above the valve 100 should be exhausted and I have, therefore, provided the valve chamber 8 with two exhaust ports 41 and 42 communicating, respectively, with the two parts of a chamber 105 43 arranged between the valve chamber 8 and the cylinder. The valve 33 has annular ports 44 and 45 so arranged that the port 44 will connect the relief port 41 with the port 28 when the latter port has been cut off from the source of fluid supply, and the 110 port 45 will connect the ports 42 and 29 when the port 29 has been cut off from the source of fluid supply. The two parts of the chamber 43 are connected by conduits 115 46 with the exhaust chamber 24. 120

The operation of the device has been fully explained in connection with the description of the several parts thereof and it will be apparent that the flow of the motor fluid to the cylinder is controlled by the piston valve 125 18 and that this piston valve is shifted, to cause the motor fluid to act upon one side or the other of the piston, by means of the motor fluid itself which is caused to act upon one end or the other of the piston 130

valve 18 by the valve 33, this latter valve being controlled by the movement of the piston of the motor. The action is positive, the valve cannot become balanced and there 5 are required no fine or delicate adjustments which would make the device impractical for service in the hands of unskilled persons.

While I have shown and described one 10 embodiment of the invention it will be understood that this has been chosen for the purposes of illustration only, and that I do not desire to be limited to the details of construction shown and described, for obvious modifications will occur to a person 15 skilled in the art.

Having thus fully described my invention, what I claim as new and desire to secure by Letters Patent, is:—

1. In a motor, the combination with a cylinder and a piston mounted therein, of a casing having two parallel valve chambers arranged along side of said cylinder, one of said valve chambers communicating with said cylinder on opposite sides of said piston and with an exhaust chamber, a piston valve mounted in said valve chamber and having an inlet port, the second of said valve chambers communicating with a source of fluid supply and having a port in permanent communication with the inlet port of said piston valve and also having other ports communicating with said first mentioned valve chamber at the opposite ends of said piston valve, a piston valve mounted in said last mentioned valve chamber and having a port to permanently connect said source of fluid supply with the inlet port for the first mentioned valve chamber, said piston valve having an axial conduit connected with said source of fluid supply, said last mentioned valve chamber having relief ports at the opposite ends thereof and said last mentioned piston valve being constructed to alternately connect the ports leading to the 45 ends of the first mentioned valve chamber with said axial conduit and said relief ports, and a motor controlled device for actuating said last mentioned piston valve.

2. In a motor, the combination with a cylinder, and a piston mounted therein, of a casing secured to said cylinder and having two parallel valve chambers, two-part chambers interposed between the respective valve chambers and said cylinder, the two parts 55 of one of said two-part chambers communicating, respectively, with said motor cylinder on opposite sides of the piston, and each having an inlet port and an exhaust port connecting the same with the 60 corresponding valve chamber, a piston valve mounted in said valve chamber and having an inlet port adapted to be moved into registration with either of the inlet ports

leading to said two-part chamber, and having exhaust ports to be moved into registration with the respective exhaust ports of said two-part chamber, the other of said valve chambers communicating with a source of fluid supply, having a passageway in permanent communication with the inlet 70 port of said piston valve and having relief ports connected respectively to the two parts of the second two-part chamber, other ports connecting said last mentioned valve chamber with the first mentioned valve chamber 75 at the opposite ends of said piston valve, a piston valve mounted in said last mentioned valve chamber to control said ports, and a device actuated by the motor piston for operating said last mentioned piston valve. 80

3. In a motor, the combination, with a cylinder, and a piston mounted therein, of a casing secured to said cylinder and having two parallel valve chambers, two part chambers interposed between the respective valve 85 chambers and said cylinder, the two parts of one of said two part chambers communicating, respectively, with said motor cylinder on opposite sides of the piston and each having an inlet port and an exhaust port, 90 connecting the same with the corresponding valve chamber, a piston valve mounted in said valve chamber and having an inlet port adapted to be moved into registration with either of the inlet ports leading to said two 95 part chamber and having exhaust ports to be moved into registration with the respective exhaust ports of said two part chamber, the other of said valve chambers communicating with a source of fluid supply, 100 having a passageway in permanent communication with the inlet port of said piston valve and having relief ports connected, respectively, to the two parts of the second two part chamber, other ports connecting 105 said last-mentioned valve chamber with the first-mentioned valve chamber at the opposite ends of said piston valve, a valve mounted in said last-mentioned valve chamber and having a longitudinal passageway 110 communicating with said source of fluid supply and having outlet ports near the opposite ends of said valve, said last-mentioned valve being arranged to alternately connect the ports leading to the opposite 115 ends of the first-mentioned valve chamber with said longitudinal passageway and the respective relief ports, and a connection between said last-mentioned valve and the motor piston. 120

In testimony whereof, I affix my signature in presence of two witnesses.

LOUIS S. RIZER.
